COMBINED SWITCH AND MICROPHONE FOR AN ACOUSTIC COUPLER

John P. Kennedy, Columbus, Ohio, assignor to
Design Elements, Inc.

Filed Jan. 3, 1972, Ser. No. 215,269

Term of patent 14 years

Int. Cl. D14—03

U.S. Cl. D26—14 A

FIG. 2

FIG. 6

FIG. 4

FIG. 1

FIG. 3

FIG. 5

FIG. 1 is a side elevation of a combined switch and microphone for an acoustical coupler showing my new design;

FIG. 2 is a top plan view thereof;

FIG. 3 is a bottom plan view thereof;

FIG. 4 is a side elevation of the microphone member with the switch omitted for ease of illustration;

FIG. 5 is a bottom plan view of the switch; and

FIG. 6 is a side elevation thereof.

I claim:

The ornamental design for a combined switch and microphone for an acoustic coupler, as shown and described.
